WITNESS:

A. F. Schläppi
INVENTOR
BY
Victor J. Evans

ATTORNEY

UNITED STATES PATENT OFFICE.

ADOLPH F. SCHLÄPPI, OF CURWENSVILLE, PENNSYLVANIA.

HOLDER.

Application filed April 23, 1924. Serial No. 708,527.

To all whom it may concern:

Be it known that I, ADOLPH F. SCHLÄPPI, a citizen of the United States, residing at Curwensville, in the county of Clearfield 5 and State of Pennsylvania, have invented new and useful Improvements in Holders, of which the following is a specification.

This invention aims to provide a dental X-ray film holder which is very simple in 10 construction, and practically indestructible with ordinary use.

The chief characteristic of this invention resides in providing a holder with which the film can be easily and quickly associated, the 15 holder being further utilized to maintain the film in proper position within the mouth by arranging the holder in a position to be clamped between the teeth.

The nature and advantages of the invention will be better understood, when the following detailed description is read in connection with the accompanying drawings, the invention residing in the construction, combination and arrangement of parts as 20 claimed.

In the drawings forming part of this application, like numerals of reference indicate similar parts in the several views, and wherein:

30 Figure 1 is a view of the holder showing the X-ray film, by dotted lines, associated therewith.

Figure 2 is a view taken at right angles to Figure 1.

35 Figure 3 is an elevation of Figure 1.

Figure 4 is a detail view of the frame.

Figure 5 is a similar view of the wedge shaped slide.

40 Figure 6 is a perspective view of the switch.

The device forming the subject matter of this invention includes a frame 10 which is tapered as shown, one side of the frame terminating to provide a flange 11 arranged at 45 a right angle to the body of the frame, while the opposite side of said body portion is provided with a flange 12 arranged parallel therewith mounted to slide between the flanges 11 and 12 is a wedge 13 which is held operatively associated with the frame by a slot and pin connection. The wedge is provided with a longitudinal slot 14 which operates beneath the parallel flange 12, the slot receiving a pin 15 which connects the 50 flange and body portion as shown. The opposite side of the wedge cooperates with the

flange 11 for clamping the X-ray film 16 between said parts as illustrated in Figure 1, so that the film can be conveniently placed within the mouth of the patient, the holder 60 constituting a finger hold for this purpose. In addition to this use, the holder in its entirety is further utilized to support the film in proper relation to the particular tooth to be X-rayed, and this is accomplished by arranging the holder between the teeth for the purpose just stated. It is desired to have it understood that the component parts of the holder can be constructed from any suitable material without departing from the spirit 70 of the invention, but is preferably composed of the combination of metal and vulcanite, gutta-percha or other material of the character to protect the surface of the teeth from being injured, while biting down or clamping 75 the holder between the teeth for the purpose just mentioned. If desired the frame can be formed with a slightly raised portion somewhat roughened to prevent slipping of the fingers or trouble incident to the use of 80 the holder, or in other words to prevent movement of the wedge with relation to the frame. The holder can be used for making a radiograph of any tooth or teeth, either 85 upper or lower.

While it is believed that from the foregoing description, the nature and advantages of the invention will be readily apparent, I desire to have it understood that I do not limit myself to what is herein shown 90 and described and that such changes may be resorted to when desired as fall within the scope of what is claimed.

Having thus described the invention, I 95 claim:

1. A dental X-ray film holder comprising a wedge shaped frame including a flange, and a wedge slidably associated with said frame and adapted to clamp said film therebetween and said flange.

2. An X-ray film holder comprising a frame tapered toward one end and having its opposite sides formed with right angularly disposed flanges, and a wedge fitted in said frame for sliding movement, and having one side movable beneath the adjacent flange, the other side of said wedge cooperating with the other flange for clamping the film therebetween for the purpose specified.

3. A dental X-ray film holder comprising a frame tapered from one end to the other, a wedge slidable in said frame and cooper-

ating with the latter to clamp the film therebetween; and said holder being adapted to be arranged between the teeth of the patient to support the film in proper position for use.

4. A dental X-ray film holder comprising a metallic frame tapered toward one end, a metallic wedge slidable on the frame and cooperating with the latter to clamp the film therebetween, a slot and pin connection be-

tween the frame and wedge, said holder being adapted to be arranged between the teeth of the patient and supporting the film in position for use, and said frame and wedge being covered by suitable material to prevent injury to the teeth incident to the biting down upon the holder. 15

In testimony whereof I affix my signature.

ADOLPH F. SCHLÄPPI, D. D. S.
